(57) **CLAIM**

The ornamental design for a travel bottle set, as shown and described.

DESCRIPTION

FIG. 1 is a perspective view of a travel bottle set showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of the portioned labeled 9 of FIG. 1 thereof.

The dash-dash broken lines depict portions of the travel bottle set that form no part of the claimed design. The dot-dash broken lines show the boundaries of the enlarged portion and form no part of the claimed design.
